[57] CLAIM

The ornamental design for a random number selector, as shown and described.

DESCRIPTION

FIG. 1 is a front elevational view of the random number selector of the present invention, the rear elevational view being a mirror image thereof;

FIG. 2 is a left side elevational view of the random number selector of FIG. 1, the right side elevational view being a mirror image thereof;

FIG. 3 is a top plan view of the random number selector of FIG. 1; and,

FIG. 4 is a bottom plan view of the random number selector of FIG. 1.

The broken lines showing of letters and numbers in FIG. 1 are for illustrative purposes only and form no part of the claimed design.
